CLAIM

The ornamental design for a chain link, substantially as shown and described.

DESCRIPTION

FIG. 1 is an end elevational view of a chain link showing our new design, the end opposite being a mirror image;

FIG. 2 is a top plan view thereof;

FIG. 3 is a side elevational view taken from the left of FIG. 1;

FIG. 4 is a bottom plan view thereof;

FIG. 5 is a side elevational view taken from the right of FIG. 1.

FIG. 2.

FIG. 1.

FIG. 3.

FIG. 4.

FIG. 5.
